UNITED STATES PATENT OFFICE.

ALBERT SLATEN, OF FARGO, NORTH DAKOTA.

BUTTER CHIPPER.

Application filed June 27, 1922. Serial No. 571,144.

To all whom it may concern:

Be it known that I, ALBERT SLATEN, a citizen of the United States, residing at Fargo, in the county of Cass and State of North Dakota, have invented certain new and useful Improvements in Butter Chippers, of which the following is a specification.

This invention relates to dispensing apparatus, and the primary object of the invention is to provide a butter dispensing machine for lunchrooms and the like, in which the butter is automatically cut into chips and delivered to butter dishes, which are in turn, moved to a dispensing position, where they can be readily grasped, said apparatus allowing the customers of the restaurant or lunch room to wait upon themselves.

Further objects of the invention, are first the provision of novel means for automatically feeding pound squares of butter to the cutting apparatus in a step-by-step motion; second, to provide novel means for cutting the squares of butter into a predetermined number of chips at desired intervals; third, to provide novel means for receiving the cut butter from the cutting mechanism; fourth, to provide novel means for dropping and guiding one butter chip at a time on butter plates; fifth, to provide novel means for carrying the butter plates past the butter chip dropping and guiding means; and sixth to provide novel means for automatically feeding one butter plate at a time to the butter plate carrying mechanism.

A further object of the invention is the provision of novel means for incorporating an ice container or a cooling casing with the improved butter chipping and dispensing machine; so that the cakes of butter and the chips already cut will be maintained in a cool and solid condition until used.

A further object of the invention is the provision of novel means for permitting the loading of the machine with the butter plates, so that a number of the said butter plates can be placed in the machine at one time and in a convenient and expeditious manner.

A further object of the invention is the provision of means for locking the machine against operation, when the supply of butter plates in the machine becomes low, said locking means being so constructed as to necessitate the placing of a new load of

butter plates in position before the machine can be again actuated, the locking means assuring against the cutting and the dropping of the butter into the machine when there are no butter plates in position for receiving the same.

A further object of the invention is the provision of means whereby the cutting wires or knives can be readily held in position and adjusted, so that any slack therein may be readily taken up, thereby allowing the efficient operation of said cutting mechanism.

A further object of the invention is the provision of a novel means for operatively connecting all of the mentioned operating parts of the butter chipping and dispensing machine to a single operating shaft, thereby allowing the machine to be operated by a hand crank or the like, which can be readily turned by the patrons of the lunchroom or restaurant.

A still further object of the invention is the provision of a novel butter chipping and dispensing machine of the above character, which will be durable and efficient in use, one that will be positive in operation, and one which can be placed upon the market at a moderate cost.

With these and other objects in view, the invention consists in the novel construction, arrangement and formation of parts, as will be hereinafter more specifically described, claimed and illustrated in the accompanying drawings, forming a part of this specification, in which drawings:

Figure 1 is a fragmentary top plan view of the improved machine, the top wall being shown removed.

Figure 2 is a vertical longitudinal section through the improved machine, taken on the line 2—2 of Figure 1.

Figure 3 is a vertical transverse section through the improved machine, taken on the line 3—3 of Figure 1, looking in the direction of the arrows and illustrating the means for receiving the butter from the cutting mechanism.

Figure 4 is a similar transverse section taken on the line 4—4 of Figure 1, and looking in the direction of the arrows, illustrating the novel cutting mechanism.

Figure 5 is an enlarged fragmentary plan view partly in section illustrating parts of the operating mechanism for the various mechanisms for the improved de-

vice, this figure showing the butter receiving means in butter engaging position.

Figure 6 is a transverse section through the forward end of the machine taken on the line 6—6 of Figure 2, illustrating the operating mechanism for permitting the delivering of one butter plate at a time to the butter carrying mechanism.

Figure 7 is an enlarged fragmentary vertical horizontal section through the machine taken on the line 7—7 of Figure 5, illustrating the cam shaft and mechanism for operating the butter chip releasing means.

Figure 8 is an enlarged fragmentary vertical longitudinal section through a portion of the machine illustrating the cam wheel and roller for actuating the butter cutting knife.

Figure 9 is an enlarged detail section taken on the line 9—9 of Figure 5, illustrating the means of mounting the sleeves for supporting the butter engaging and releasing means on its supporting shaft.

Figure 10 is an enlarged vertical section through the forward portion of the apparatus illustrating the butter plate carrying means and the arms for releasing one plate at a time to the butter plate carrying means.

Figure 11 is a fragmentary vertical section through the butter plate feeding means taken on the line 11—11 of Figure 6, said section illustrating the means for operating the releasing arms for the butter plates.

Figure 12 is an enlarged fragmentary longitudinal section through a portion of the machine illustrating the means for permitting the butter plates having butter chips thereon to be dropped or delivered to the dispensing platform.

Referring to the drawings in detail, wherein similar reference characters designate corresponding parts throughout the several views, the letter A indicates the casting of the improved apparatus; B, the means for feeding the squares or cakes of butter to the cutting mechanism in a step by step motion; C, the cutting mechanism for periodically cutting the squares or cakes of butter into a predetermined number of chips; D, the means for receiving and carrying the cut butter chips away from the cutting mechanism C; E, the means for releasing and guiding the cut butter chips one at a time into butter plates; F, the means for carrying the butter plates past the butter chip releasing and guiding means; G, the chute for the butter plates; H, the novel means for dropping one butter plate at a time to the butter plate carrying means F from the chute G; I, the loading means for facilitating the placing of the plates in the chute; J, the locking means for preventing actuation of the apparatus

when the supply of plates in the chute runs low; and K, the means for guiding the butter plates containing the cut butter chips into a dispensing position.

The casing A can be constructed in any desired way and of any preferred material and it is contemplated making the same out of porcelain or the like so that the same will present a pleasing appearance. As shown, the casing A includes an outer shell 15 and an inner spaced shell 16 defining an intermediate compartment 17, in which can be placed ice or some other cooling medium, so that the butter will be maintained in a cool and firm condition.

The ice compartment 17 may be constructed so that a circulation of air may be had through the same if so desired. As shown the inner casing includes the side walls 18 and 19, the rear wall 20, the front wall 21, and the bottom wall 22. The outer shell 15 includes the side walls 23 and 24, the rear wall 25 and the bottom 26. The side walls 18 and 19 of the inner shell 16 and the side walls 23 and 24 of the outer shell 15 abut the front wall 21 as is clearly shown in Figure 1 of the drawings. The shells 15 and 16 may be maintained in their spaced relation by a suitable spacing member 28 and the inner surfaces of the shells 16 may be provided with a suitable metal lining if so desired. The forward end of the compartment 17 is closed by a cross strip 29 which defines a forward delivery compartment 30, the forward end of which is left open. The front end of the lower wall 26 of the casing forms a delivery platform 31 for the delivery compartment 30. A transverse partition 32 can be disposed in the inner shell 16 adjacent and in spaced relation to the front wall 21, and this partition 32 defines a front chamber 33 in which is positioned the chute G for the butter plates and in which is adapted to travel a portion of the butter plate carrying means F. The partition 32 defines a rear compartment 34, in which is positioned the butter cake feeding means B; the cutting mechanism C; the butter engaging means D; the butter dropping and guiding means E; and other various operating portions of the device. It can be seen that the lower end of the partition 32 is spaced from the lower wall 22 of the inner shell, which permits the extending of the butter plate carrying means F into the compartment 33 and into the compartment 34.

The butter square or the cake feeding means B includes a longitudinally extending frame 35 and a transverse frame 36. The frame 35 supports a guiding means 37 for the squares or cakes of butter. This guide includes the longitudinally extending tracks 38, the outer side edges of which may be upturned to provide guide flanges 39. The

guide means 37 may be of a sufficient length so that two or three pound cakes or squares of butter can be placed on the same. The transverse frame 36 includes the upstanding 5 posts 40, which are spaced a sufficient distance to enable a pound square of butter to ride between the same. These posts are braced by transversely extending upper and lower bars 41 and 42. The lower cross bar 10 42 forms means for supporting the forward ends of the guide means 37 for the butter. The transverse frame 36 also supports a part of the cutting mechanism C which will be hereinafter more fully described.

15 A follower block 43 having substantially the same area as the cross sectional area of a cake of butter is slidably mounted within the guide 37, and this follower block is adapted to force the pound cakes or squares 20 of butter toward the cutting mechanism C. This block may have secured to its rear face a base plate 44, which carries an outwardly extending arm 45. This arm 45 is provided with a bearing 46 for slidably engaging a 25 longitudinally extending guide rod 47, which may have its terminals secured in place against movement in any preferred manner. The extreme outer end of the arm 45 carries a clutch 48, for gripping the reciprocating 30 operating rod 49. The outer end of the arm 45 is provided with an opening for receiving the reciprocating rod 49 and the clutch 48 consists of a flat plate pivotally secured as at 50 to the arm. This clutch plate 48 is 35 provided with an opening through which the reciprocating operating rod extends and this clutch plate is so associated with the arm 45 that upon rearward movement of the rod 49, the plate 48 is swung on its pivot until 40 the opening formed therein will register with the opening formed in the arm 45, thus permitting free sliding movement of the operating rod 48 in a rearward direction. Upon the forward movement of the arm 49, 45 the clutch plate 48 will be moved forward and the openings formed in the plate 48 and the arm 45 will be moved out of alignment with one another thus causing a binding action upon the reciprocating rod 49 50 which will move the block 43 forwardly a predetermined distance, so as to guide the butter cakes toward the cutting mechanism. The rear end of the rod 49 is slidably mounted within a suitable bearing or guide 51, 55 which is secured to the rear wall 20 of the inner shell 16. The forward end of the rod 49 is slidably mounted within a guide 51 which can be secured to the transverse frame 36. This reciprocating rod 49 is connected 60 with the operating parts of the apparatus in a novel manner as will be hereinafter more fully described.

The cutting mechanism C includes a pair of cross wires 53 and 54, and these wires 65 are adapted to divide a butter cake into four equal longitudinal parts as the butter cake is fed forwardly. It can be seen that these wires 53 and 54 are carried by the side edges of the transverse frame 36 and the wires can be secured in any preferred 70 way to the frame, but it is preferred that the same be secured in place so that the same can be removed when they become broken, and so that any slack which may occur therein can be taken up. As shown in Figure 2 of the drawings, it is desirable to have one end of the wires anchored as at 55 and the opposite end slidably held in place by a nut or the like 56. It is to be understood, of course, that the terminals of the wire are threaded through suitable openings 57 formed in the transverse frame 36. The cutting mechanism C also includes an oscillating knife 58, which is adapted 75 to cut the cutter transversely so as to separate the same into chips. This oscillating knife 58 includes an open frame 59, the arms of which support a cutting wire 60. The lower terminals of the arms may be grooved to form a guide for the cutting wire and one arm can be provided with an eye 61, to which one end of the wire can be attached. The other end of the wire may be attached to a threaded rod 62, which 80 may be extended through a guide eye 63 and have threaded thereon a suitable turn nut or the like 64. It can be seen that by adjusting the turn nut 64, that the tension of the wire 60 can be readily adjusted. The frame 59 is provided with an outwardly extending shank 65 and the outer end of this shank can be bifurcated as at 66, and has secured thereto a suitable bearing sleeve 67. This bearing sleeve 67 is adapted to be 85 mounted upon a supporting pin 68, which can be secured to the side wall 19 in any preferred manner. This cutting knife 58 is oscillated by a mechanism which will be hereinafter more fully described. The knife 58 is actuated at certain intervals so that the butter chips will have time to be 90 guided and dropped onto the butter plates between the cutting operations.

95 The means E for receiving the cut butter chips from the cutting mechanism consists of a plurality of arms 70. As shown the arms 70 are four in number, one for each butter chip, and these arms have their inner ends provided with right angularly disposed feet 71 which are mounted for swinging movement in bearings 72 carried by a disc 73. This disc 73 is secured adjacent to the rear end of a sliding sleeve 74, reciprocably mounted upon a second sleeve 75. This second sleeve 75 is formed relatively long and is mounted for rotary movement upon an inwardly extending shaft 76, which can be secured in any preferred manner to the partition 32. In order to permit sliding movement of the sleeve 74 on the sleeve 75 and 100

105

110

115

120

125

130

synchronous rotary movement with the same, the sleeve 74 is provided with an inwardly extending pin 77, which is mounted in a slot 78 formed longitudinally of the 5 inner or second sleeve 75. The inner end of the sleeve 74 is provided with a second rigid disc 79, and this disc 79 is provided with oppositely bent out tongues 80, which define guide slots 81 for the arms 70. These 10 arms 70 are normally maintained in engagement with the disc 79 and with a disc 82 by means of springs 83. The disc 82 is secured to the inner end of the sleeve 75 and forms means for spreading the arms 70 15 against the tension of the springs 83 as will hereinafter more fully appear. The disc 82 may also be provided with guide pins 85 for the arms 70 if so desired. As clearly shown, the guide pins 85 are arranged in 20 pairs and extend radially from the disc 82. The inner ends of the arms 70 are provided with inwardly bent portions 86 and it is obvious that when the arms are moved back and the bent portions 86 are in engagement 25 with the disc 82, that the arms will spread against the influence of the springs 83. These arms 70 may be provided with extensions 87 which are in alignment with the bent portions 86, so as to maintain the arms 30 70 in their spread position for a considerable length of time. Beyond the bent portion 86, the arms 70 are bent outwardly as at 88 and the terminals thereof are bifurcated and sharpened to provide butter engaging forks 89. The sleeve 75 has keyed or 35 otherwise secured thereto a relatively large gear wheel 90 and this gear wheel is operated by a means which will hereinafter more fully appear. The sleeve 74 can also be provided with a rotatable collar 91 carrying 40 outstanding pins 92 which can be engaged by the yoked end 93 of the lever 94, which is operated by a means which also will be hereinafter more fully described. It is ob- 45 vious, however, that when the lever 94 is rocked, the disc 73 and the arms 70 will be moved back and forth on the sleeve 75, while the sleeve 75 is being rotated. The 50 extreme inner end of the shaft 76 can be provided with a stop disc or head 95 and if desired, the disc 79 can be provided with stops and guide pins 96, which are adapted to extend through suitable openings formed in the disc 82 engage the rigid disc 95, so 55 that all of the parts will be locked against movement, when the same are in one position, that is, when the forks 89 are forcibly moved into engagement with the butter chips. 60 The means E for releasing and guiding the chips one at a time into the butter plates which are indicated by the reference character L and which are brought one at a time past the butter chip dropping and guid- 65 ing means E by the carrying means F con-

sists of an arcuate arm 100 which extends inwardly and downwardly from a supporting bracket 101 which can be secured to the inclined platform 102 in any preferred manner. This platform 102 is merely provided as a support for the certain operating parts of the device and extends inwardly from the transverse partition 32 to the bottom wall 22. Disposed above and in spaced relation to the arcuate arm 100 is a depending arm 103 which can be soldered or otherwise secured as at 104 to the rigid disc 95. The lower free end of the rod 103 can be provided with an arcuate portion 105, if so desired. Now, it is obvious that when the forks 89 have been moved inwardly into forcible engagement with the chips of the butter cut and then rearwardly, that as the arms 70 ride between the arcuate arms 100 and 103 and are reciprocated back and forth by the lever 94 which will be hereinafter more fully described, that the butter chips will be forced off of the forks, where they will drop downward onto the butter plates L which are carried past by butter plate carrier F. In order to insure the falling of the butter chips on to the butter plates, an inwardly extending guide arm or rod 106 is carried by the wall 18, and the inner end of this rod is provided with a depending guide foot 107. As the butter falls upon the plates L from the butter dropping and guiding means E in a substantially straight path, there is a likelihood of butter standing up on the plates or on their edges and in order to throw the butter chips flat on the butter plates, the arm 108 is provided. This arm 108 can also be carried by the wall 18 and extends downwardly and forwardly from the wall in an arcuate path and terminates in substantially a hook shaped member 109. As this hook shaped portion 109 of the arm 108 is disposed in the path of the butter plates after the same rides by the butter dropping and guiding means E, it is obvious that the hooked end will draw the butter chips downward flat upon the plate.

The butter carrying means F comprises a circular turn table 110 which is provided with a plurality of spaced openings 111 arranged in annular formation for the reception of the butter plates L. It can be seen that the butter plates L will fit into the openings and rest upon the lower wall 22 and that as the turn table is rotated by means hereinafter more fully described, the butter plates will be moved over the upper surface of the wall 22. Now, this turn table 110 is secured in any preferred manner to the axial vertically disposed shaft 112, which can be mounted for rotary movement in a bearing 113 and a bearing 114, secured to any preferred rigid part of the casing A. This shaft 112 has keyed there-

to a relatively large gear wheel 115, which is adapted to be engaged by the operating mechanism, which as stated, will be hereinafter more fully described. This turn

6 table rides under the butter plate chute G and then under the butter chip dropping and guiding means E and then past the butter plate guiding means K.

The chute G for supporting the butter 10 plates L consists of a vertically disposed tube or the like 116. This tube can be formed of metal, if so desired, and has a diameter slightly larger than the butter plates L, so as to permit the easy movement 15 of the butter plates therethrough. This chute can be held in position by suitable brackets 117 if so desired. The forward portion of the chute can be provided with a vertically disposed slot 118, which facil-

20 tates the placing of the butter dishes therein as will be hereinafter more fully described. The extreme lower end of the tube, which is left open, is also provided with oppositely disposed cut out portions 25 119, in which are adapted to extend the releasing arms 120 and 121. These rock-

30 able plate engaging and releasing arms 120 and 121 are of the same construction and each including parallel spaced rods 122 and end bars 123, which support bearing studs 124, which can be rotatably mounted in suitable bearings. These arms are so ar-

35 ranged that when the same are disposed in a vertical plane, the rim of the butter dish will be rested between the upper and lower bars 122 and when the same are rocked in one direction a butter plate will be released, and permitted to fall in an opening 111, which may be directly below the same at

40 that time. This movement, of course, will spread the lower bars 122 outwardly and move the upper bars 122 inwardly and hold the other plates against falling movement.

When the arms are rocked in their opposite 45 directions, the lower bars 122 will be moved inwardly while the upper bars 122 will be moved outwardly, thus permitting another plate to drop into releasing position and between the upper and lower bars 122 of

50 the rocking arms 120 and 121. The studs 124 of the rocking arms 120 and 121 at the rear ends of the arms are secured respectively to levers 125 and 126, which have their inner ends connected by slot and pin

55 connections 127. The lever 126 is of a bell crank formation and has the operating arm 128 thereof connected by a link 129 to an operating crank 130, which is keyed or otherwise secured to an operating shaft 131,

60 which is actuated by the operating means of the apparatus, which, as stated, will be hereinafter more fully described. It can be seen, however, that during the rotation of the shaft, the arm 128 will be rocked back and forth through the medium of the

links 129, and levers 126 and 125 will rock the arms 120 and 121 in the manner just described.

In order to facilitate the placing of the butter dishes or plates L, in the chute G, 70 the loading means I is provided. This means I consists of a relatively long tube 132, which has a diameter slightly less than the tube 116, so that the same can readily fit within the tube 116. This loading tube 75 132 is adapted to receive a plurality of the dishes and the dishes are held against falling movement from the lower end of the tube 132 by sliding plate 132'. When the tube 132 has been placed within the tube 116, the sliding plate 132' can be easily withdrawn through the slot 118 formed within the tube 116 as hereinbefore described.

It is essential that some means be provided 80 for preventing the operation of the machine when the supply of butter plates or dishes L becomes low, so that the butter will not be dropped in the machine without any butter plates to receive the same and in 90 order to lock the machine against operation in this contingency, the locking means J is provided. This locking means J consists of a swinging lever 133, which is held in place at its upper end by a pivot pin 134.

95 This lever is adapted to normally extend into the chute G through a slot 135 formed therein, and when the plates are moved into the chute, the lever 133 will be swung outwardly as is readily apparent. This lever 133 has pivotally secured thereto intermediate its ends by a pin 136, a rod 137, which is secured to one arm of the bell crank 138. This bell crank 138 is mounted upon a pivot pin 139 at its angle and its arm, which 100 has not been mentioned has pivotally secured thereto a stop rod 140, which is normally urged into the path of the operating crank 141 for the operating parts of the machine, which will be hereinafter more 105 fully described, by the contractile coil spring 142, which engages the first mentioned arm of the bell crank and a rigid portion of the frame or casing A of the machine. Now, it can be seen that as the 110 dishes are moved out of the chute G or below the lever 133, that the lever 133 will be swung inwardly by the spring 142, which will in turn move outwardly the arm 140 into the path of the crank 141, as stated, 115 and thus prevent the movement thereof.

When the chute is filled with dishes, however, the lever 133 will be forced outwardly swinging the bell crank 138 on its pivot 139 against the influence of the spring 142, 120 which will move the rod 140 inwardly out of the path of the operating crank 141.

Now, as heretofore stated, the turn table 110 is adapted to move the dishes from the chute past the cutting mechanism C and 130

the butter dropping and guiding means E and then to the means K for guiding the butter plates to the dispensing platform 31. The means K for guiding the plates containing the butter to the dispensing platform 31 may be of any preferred character and by way of example, the means has been shown to consist of a platform 145, which is pivoted at its inner end upon a suitable pin 146. The platform 145 is normally maintained in a raised position by a contractile coil spring 147 which is secured to the door 145 and to an eye 148 carried by the casing A. Now, the turntable 110 is adapted to move the dishes containing the butter on to the door or platform and the weight of the dishes will overcome the tension of the spring 147, and thus permit the lowering of the trap door and permit the dishes to slide down the same on to the platform 31 as is readily apparent.

The operating means which has been designated by the reference character M consists of a main operating shaft 150 which is mounted in suitable bearings 151 carried by the frame A of the apparatus. This shaft 150 is adapted to be turned by the hand crank 141 which can be rotatably mounted for movement thereon if so desired and provided with a clutch face 152, which is adapted to engage a rigid clutch section 153 and which is normally moved into engagement with the clutch section 153 by a spring 154, which can be coiled about the shaft 150. This is to prevent retrograde movement of the shaft 150 by the hand crank 141. The inner end of this shaft 150 has keyed or otherwise secured thereto a pinion 155, which meshes with a relatively large gear wheel 156 which is keyed or otherwise secured to a counter shaft 157, which can be mounted in suitable bearings 158 carried by the casing for that purpose.

The inner face of the relatively large gear wheel 156 has secured thereto at one side of the axis, a bracket 159, which is slotted for the reception of a pin 160. This pin is held in any preferred adjusted position in the slot for a purpose which will hereinafter more fully appear. This pin has pivotally secured thereto a connecting link 161, which in turn has its inner end pivoted as at 162 to the reciprocating operating rod 49 of the butter chip feeding means B. Thus it is obvious that when the gear wheel 156 is turned, the operating rod 49 will be reciprocated back and forth. Now, it is often desired that different widths of the butter chips be cut and in order to adjust the width of the cut, the pin 160 is adjusted in the slot formed in the bracket 159 toward or away from the axis of the gear wheel 156, which of course, will regulate the stroke of the reciprocating operating rod 49, and thus control the movement of the follower block 43. The frame

59 of the cutting knife 58 is oscillated up and down by means of a connecting rod 163, which is pivotally connected to the shank portion 66 as at 164'. The inner end of this connecting link or rod 163 is pivotally connected to an oscillating U-shaped yoke 164, which is mounted at its bight portion in suitable bearings 165 carried by the inclined support or table 102. The innermost arm of the oscillating frame 164 has secured thereto a roller 166, which is mounted within the elliptical shaped cam track 167, which is secured in any preferred manner to the outer face of the main operating gear wheel 156. Now, it is obvious that during the rotation of the gear wheel 156, that the U-shaped yoke 164 will be raised and lowered by the roller 166 and the elliptical shaped cam track 167, which, of course, will actuate the connecting rod or link 163 up and down, consequently oscillating the cutting knife 58, moving the same back and forth across the butter cake to be cut. This operating means for the cutting knife 58 is synchronized with the butter receiving means D, as will now be described. The gear wheel 156 is provided with spur teeth, which mesh with the pinion 155 as heretofore described, and this gear is also in the nature of crown gear as the inner face thereof is provided with inwardly extending gear teeth 168. These teeth are, however, interrupted for a portion of the circumference of the gear 156, and in this smooth portion of the gear is disposed an arcuate locking plate 169. The gear teeth 168 are adapted to be engaged by a pinion 170 which is keyed or otherwise secured to a longitudinally disposed counter shaft 171 which can be mounted in suitable bearings 172 carried by rigid portions of the frame or 100 casing A of the improved apparatus. The shaft 171 has secured to its forward end a head 173, which is provided with a flat face 174, and the shaft 171 is so timed with relation to the gear 156 that this flat face will 110 be in alignment with the lock arcuate plate 169 when this plate moves past the gear 170. Thus it can be seen that when the teeth 168 are out of mesh with the teeth of the pinion 170 that the lock plate 169 will engage the 115 flat face 174 of the head 173 and thus absolutely preclude this shaft against accidental movement. The forward end of the shaft 171 has secured thereto a pinion 175 which meshes with an idle pinion 176, which in turn meshes with the relatively large gear wheel 90 secured to the rotatable sleeve 75 of the butter receiving means D. It is thus obvious that during the rotation of the gear wheel 156 that the sleeve 75 will be rotated, and consequently the arms 70 moved past the butter chip releasing and guiding means E.

The shaft 171 is held against movement by the lock plate 169 so that when the arms 70 130

have been forcibly moved inward into engagement with the butter chips, the same will be held stationary against movement while the butter chips are being cut off from the cake and the cam 167 is so disposed on the gear 156 that the knife will be moved downward just after the forks 89 have been stuck into the butter chips by forward movement of the arms 70. The sleeve 74 is reciprocated back and forth on the sleeve 75 during the rotation thereof by the lever 94 as heretofore stated, and this lever is operated by means which will now be described. As clearly shown in the drawings, however, the lever 94 is pivotally mounted intermediate its ends upon a suitable pivot pin 177 carried by a bracket 178 which can be secured to the transverse partitions 32. The outer end of the lever 94 has pivotally connected thereto by means of a pin 179 an inwardly extending link 180, the inner end of which is pivotally connected as at 181 to a crank arm 182, which is formed upon a sleeve 183. This sleeve 183 is rockably mounted upon the shaft 150 and carries the inwardly extending crank arm 184. The inner end of this arm or crank 184 carries a roller 185, which is adapted to engage the periphery of the cam wheel or track 186, which is of a special configuration as will now be described. This cam wheel or track 186 includes a disc plate 187, which is keyed or otherwise secured to the counter shaft 157. The roller 185 is normally maintained in engagement with the periphery of the track 186 by means of a relatively strong contractile coil spring 188 which is secured to the crank arm 182 and to the transverse partition 32, and the spring also serves as means for forcibly urging the forks 89 into the butter chips. This cam track 186 consists of a plurality of arcuate depressions 189 and the curved portions of the depressions 189 are all the same distance from the axis of the disc plate 187 and these depressions are disposed at quarters on the plate 187. As shown, there are three of the depressions and the first and last of these depressions are, of course, spaced from each other, which forms an abrupt throw extending from the periphery of the track to the axis of the plate 187 and extending from the axis of the plate is a cam lift 190 which extends toward the first depressions 189.

Now, in operation of the improved apparatus, during the actuation of the shaft 157, by the main operating shaft 150 through the medium of the gears 155 and 156, the cam 186 will of course, be rotated, and as the roller 185 falls into the depressions 189, the lever 94 will be rocked at its pivot 177, thus moving the sleeve 74 back and forth on the sleeve 75 as the sleeve 75 is rotated by the wheel 90 and the means heretofore described.

Now, when the roller 185 reaches the end of

the cam track 186, the same will roll off the cam track toward the axis of the plate 187, which will allow the spring 188 to forcibly rock the sleeve 183. The forcible rocking of the sleeve 183 will actuate the inner end of the lever 94, thus sliding the sleeve 74 to its fullest extent and moving the forks into engagement with the butter chip at which time the shaft 171 will be held against rotation by the lock plate 169. Immediately after the forks 89 have been moved into engagement with the butter, the knife 58 will be moved downwardly by the cam track 167 and thus the butter chips will be severed from the main portion of the butter. The knife will be immediately raised by the cam track 167 and the roller 185 will engage the curved portion 190 of the cam track 186. This will gradually move the arms 70 inwardly and the inclined portions 86 of the arms will engage the guide disc 82 and be gradually spread open, during gradual movement back of the arms 70, the sleeve 75 will of course be rotated, and the chip of butter carried by one arm will be moved past the butter chip releasing and guiding means E, and as the arm is drawn inwardly, the first piece of butter will be dropped upon one of the butter plates L. The roller will now drop into the first depression 189 which will permit the inward movement of the arm 70 of the shaft again a slight distance, and as the wheel 187 continues to rotate, the roller 185 will gradually ride out of the depression and thus move the arm 70 again inwardly of the chip releasing and guiding means E, while the sleeve 75 is rotating, which will allow a second chip of butter to be released. This operation is continued until all four of the chips of butter are released from the forks 89 at which time the forks will again be forced into engagement with the butter. The shaft 131 utilized for actuating the arms 120 and 121 of the butter plate releasing means H merely forms a continuation of the shaft 171. Thus it is obvious that during the operation of the shaft, the dish releasing or rocking arms 120 and 121 will be operated. The operating means for the turn table 110 includes a vertically disposed shaft 200 which is provided with a pinion 201 which meshes with the relatively large pinion 115 carried by the actual portions of the turntable 110. The upper end of the shaft 200 has secured thereto a bevelled gear 201 which meshes with a bevelled gear 202 carried by the shaft 171. Thus it can be seen that during the operation of the shaft 171, the turntable will be actuated.

From the foregoing description, it can be seen that an improved and simple machine has been provided for effectively cutting up pounds of butter into chips and automatically delivering the same one at a time to

butter plates, which are then moved to a dispensing position where the same can be readily obtained by the patrons of the dining room.

5 Changes in details may be made without departing from the spirit or scope of this invention; but,

I claim:

1. A butter cutting and dispensing machine comprising means for receiving a cake of butter, a cutting mechanism, means for periodically feeding the butter forwardly to the cutting means, means for receiving the butter after the same has been cut, means for feeding butter plates past the cutting means, and means for dropping the butter cut from the receiving means onto said butter plates.

2. In a butter chip cutting and dispensing machine, the combination of means for cutting squares of butter into chips, means for receiving the chips of butter after being cut, means for carrying butter plates past the cutting means, means for feeding butter plates one by one to the butter plate carrying means, and means for removing the chips of butter from the chip receiving means and delivering a single chip of butter to each plate as the same is carried past the butter cutting means.

3. In a butter chip cutting and dispensing machine, the combination of means for cutting squares of butter into chips, reciprocating means for engaging the butter chips during the cutting operation, means for feeding plates past the butter chip cutting means, and means disposed in the path of reciprocating butter chip engaging means for forcing the butter chips off of the reciprocating butter chip engaging means and for guiding the same on to the butter plates.

4. In a butter chip cutting and dispensing machine, means for cutting squares of butter into chips, means for placing the butter chips upon plates consisting of a plurality of arms for engaging the butter during the cutting operation, a supporting shaft, a rotatable sleeve mounted upon the shaft, a reciprocating sleeve mounted upon the shaft for rotary movement therewith for supporting the arms, means disposed in the path of the arms for removing the butter chips therefrom, and means for synchronously rotating the first mentioned sleeve and for reciprocating the second mentioned sleeve.

5. In a butter chip cutting and dispensing machine, the combination of means for cutting squares of butter into chips, and means for placing the chips one by one on independent plates consisting of a supporting shaft, a sleeve rotatably mounted upon the supporting shaft, a second sleeve mounted upon the first mentioned sleeve for movement therewith and for reciprocating move-

ment thereon, a plurality of arms pivotally secured to the second mentioned sleeve, the forward ends of the arms being bent inwardly, a rigid disc carried by the first mentioned sleeve and disposed in the path of the inwardly bent portions of the arms for permitting outward movement of the arms during reciprocation of the second mentioned sleeve, butter engaging forks formed on the extreme inner ends of the arms, means for synchronously rotating the first and second mentioned sleeves and for reciprocating the second mentioned sleeve, means disposed in the path of the forks for removing the butter therefrom, as the forks are rotated and reciprocated past said last mentioned means.

6. In a butter cutting and dispensing means, the combination of means for cutting squares of butter into chips, means for placing the chips upon plates, means for feeding plates past said butter chip placing means, said butter chip placing means including a supporting shaft, a sleeve rotatably mounted upon the supporting shaft, a sleeve mounted upon the first mentioned sleeve for movement therewith and for reciprocatory movement thereon, a disc slidably carried by the second mentioned sleeve, a plurality of arms pivotally secured to the disc, a rigid disc carried by the first mentioned sleeve, the arms having their inner ends provided with inwardly extending bent portions for engaging the second mentioned disc, resilient means for normally holding the arms in engagement with the second mentioned disc, forks formed on the inner ends of the arms for engaging said discs during the cutting operation, rigid means for removing the butter chips from the forks, the forks being moved, one by one past said rigid butter chip removing means during the reciprocation of said second mentioned sleeve.

7. In a butter chip cutting and dispensing machine, the combination of means for cutting squares of butter into chips, a plurality of forks for engaging the butter chips during the cutting thereof, means for removing the butter chips from the forks, and means for moving the forks one by one and inwardly of the butter chip removing means.

8. In a butter chip cutting and dispensing machine, the combination of means for cutting squares of butter into chips, a plurality of forks, means for forcibly moving the forks into engagement with the butter during the cutting operation, an arcuate arm for moving the butter from the forks, and means for reciprocating and turning the forks past said arcuate arm one by one.

9. In a butter chip cutting and dispensing machine, the combination of means for cutting squares of butter into chips, a plurality of butter chip engaging forks, means for forcing the forks into engagement with the butter during the cutting operation,

means for drawing the forks outwardly of the butter, a pair of angularly disposed rigid arms disposed in the path of the forks, means for turning and reciprocating 5 the forks past the rigid arms to permit the butter chips to be withdrawn from the forks, butter plate carrying means disposed below the arms for receiving the butter therefrom, and a second arm disposed in the 10 path of the butter carrying means for engaging the chips to insure the laying thereof flat on the butter plates.

10. In a butter chip cutter and dispensing machine, means for cutting squares of butter into chips comprising a longitudinally extending guide for the squares of the butter, a follower plate for the butter reciprocably mounted in the guide, cross wires arranged in front of the guide for cutting the 20 squares of butter longitudinally, an outwardly extending arm carried by the plate, a reciprocating rod, a clutch carried by the follower arm for engaging the rod, an operating knife for cutting the squares of butter transversely in front of the cross rods, and means for raising and lowering the 25 knife at predetermined intervals.

11. In a butter chip cutting and dispensing machine, means for cutting the butter into 30 chips consisting of cross wires for dividing squares of butter longitudinally, a follower plate for forcing the squares of butter into engagement with the wires, means for moving the follower plate in a 35 step by step motion, an operating knife for cutting the squares of butter transversely in front of the cross wires, butter engaging forks, means for forcibly moving the forks into engagement with the butter in advance 40 of the cross wires, and means for moving the operating knife downwardly while the forks are in engagement with the butter.

12. In a butter chip cutter and dispensing machine, means for cutting the butter into 45 chips consisting of a guide for the squares of butter, a plurality of cross wires carried by the forward end of the guide, a follower block slidably mounted in the guide for forcing the square of butter into engagement with the cross wires, the cross wires being adapted to divide the butter longitudinally, a reciprocating rod, a clutch carried by the follower block for locking engagement with the rod during forward 50 movement thereof, a gear wheel, means for operating the gear wheel, a pitman rod operatively connecting the reciprocating rod with the gear wheel, and means for moving the pitman rod toward and away from the axis of the gear wheel to vary the stroke of 55 said reciprocating rod.

13. In a butter chip cutting and dispensing machine, means for cutting squares of butter into chips, a turntable having recesses therein for butter plates, means for 60

operating the turntable for moving the butter plates past the butter cutting means, and means for feeding the butter plate to the turn table one by one at predetermined intervals and means for releasing the butter 70 plates from the turn table after the butter chips have been placed thereon.

14. In a butter chip cutting and dispensing machine, means for cutting squares of butter into chips, a turntable having openings therein for receiving butter plates, means for rotating the turn table for moving the butter plates past the butter cutting means, means for feeding butter plates to the turn table including a vertically disposed chute, the opposite sides of the chute at the lower end thereof having cut out portions, a pair of rocking arms disposed in the cut out portions for engaging the butter plates, said rocking arms including upper and lower parallel disposed cross bars and bearing studs disposed intermediate the cross bars at the ends of the arms, and means for rocking the arms for causing the cross bars to move toward and away from 85 the edges of the chute.

15. In a butter chip cutter and dispensing machine, the combination of means for cutting squares of butter into chips, means for receiving the butter from the cutting means, means for dropping butter chips one by one on butter plates, a turntable for moving the butter plates past the butter chip receiving means, a supply chute for feeding the butter plates to the turn table, operating means including a hand crank for the butter cutting means, the turntable, and the butter receiving means, and means for locking the machine against operation when the supply of butter plates in the chute runs 90 low.

16. In a butter chip cutting and dispensing machine, the combination of a casing having an ice compartment therein, means for cutting squares of butter into chips, a turn table for carrying butter plates past the cutting means, means for receiving the butter chips from the cutting means for dropping the chips in the butter plates, means for delivering butter plates to the turn table including a chute, operating means for the cutting means, the turntable, and the butter chip engaging and dropping means including a hand crank, a lever pivotally secured at its upper end to the chute, means normally urging the lever into the chute, the plates being normally adapted to hold the lever out of the chute, a bell crank, a stop lever secured to one arm of the bell crank for movement into the path of the operating portion of the machine, and means for connecting the other arm of the bell crank with the lever.

17. The combination with butter plate receiving means including a delivery chute,

- means for feeding butter plates one by one from the delivery chute, a removable supply chute for receiving a plurality of butter plates, a slide carried by the lower end of the supply chute, the delivery chute having a slot formed therein for permitting the movement of the slide out of the delivery chute when the supply chute is moved into said delivery chute.
18. In a butter chip cutter and dispensing machine, means for cutting the butter into chips, a supply chute, a turn table for carrying the butter plates from the supply chute past the butter cutting means, a pivoted trap door disposed in the path of the turn table, means normally holding the trap door in a raised position, the butter plates being adapted to be moved upon the trap door by the turn table, the weight of the butter plates being greater than the tension of the spring whereby the butter plates will be permitted to fall below the turn table.
19. In a butter chip cutting and dispensing machine, means for cutting butter into chips, a turn table for movement past the butter chip cutting means, a chute for supplying butter plates to the turn table, and means for delivering the butter plates one at a time at predetermined intervals to the turn table including a pair of oppositely disposed arms, each of said arms consisting of upper and lower parallel disposed bars, between which a plate is adapted to rest, pivoted studs disposed at the ends of the arms and between the parallel bars, bearings engaging in the studs, rearwardly extending levers connected with the arms, a slot and pin connection connecting the inner ends of the levers together, an operating shaft, a crank carried by the operating shaft, a link pivotally secured to the outer end of the crank, and means operatively connecting the link with one of the levers carried by said rocking arms.

ALBERT SLATEN.
